United States Patent Office.

JACOB HEPPERLY, OF PEORIA, ILLINOIS.

Letters Patent No. 94,314, dated August 31, 1869.

IMPROVEMENT IN WATER-WHEELS.

The Schedule referred to in these Letters Patent and making part of the same.

To all whom it may concern:

Be it known that I, JACOB HEPPERLY, of the city and county of Peoria, and State of Illinois, have invented a new and improved Water-Wheel; and I do hereby declare that the following is a full, clear, and exact description of the construction and operation of the same, reference being had to the accompanying drawings, making a part of this specification, in which—

Figure 1 is a perspective view.

Figure 2 is a vertical section.

Figure 3 is a perspective view of the lower side of chute-box.

Figure 4 is an imaginary section of chutes and water-wheel below.

Figure 5 is a perspective view of water-wheel.

Figure 6 is a plan view of chute-box, the dotted lines showing the gates.

Figure 7 is a plan view of water-wheel.

Like letters in the figures of the drawings indicate like parts.

This water-wheel is designed to be a portable one, as the whole apparatus can be used for many purposes where a stream or even a current of water through pipes, is available; as from hydrants, from water-works, or reservoirs.

I construct the reservoirs A of any desirable shape, cylindrical is preferable, closed at the top, except for admission of water by the pipe U, by a strong plate, B, bolted through the top of the reservoir to the flange n, but having an opening in the centre for the wheel or power-shaft f.

When a full head of water is available, it may be admitted by the vertical nozzle U, above mentioned, to which a pipe may be screwed, or otherwise fixed, or it may receive the spout of chute or funnel even.

When a lower head of water is running, it may be induced through the opening V in the side of the reservoir.

A short distance above the chutes leading to the wheel, I place a screen or grating, h, to catch all sticks, twigs, leaves, &c., from clogging the chutes or wheel, which substances may be removed through the man-hole or sliding hatch W, giving access to the space above and below the grating at the same place.

The lower edge of the reservoir A rests on the surface of the circular frame or flange n, also flush against the vertical sides of the shoulder i of the chute-box.

The bottom of the reservoir is closed by the gates or circular hatches a a, on arms radiating and centred on the box, round the "shaft-tube" g, which shut off the water from the real bottom of the reservoir, formed by the horizontal chute-box C. The flange or shoulder i of the latter rests on the circular frame or supporter n, which supports the whole machine.

The chute-box is pierced with several oblique chutes a a, or inclined-passages for water to the rotary wheel below the box, the course of each chute being the arc of a circle, and are arranged around the outward limits of the box.

The chutes a a are carried downward at a sufficient angle to gain the utmost amount of force in rotating the wheel D below which such an application of water-power will give.

The water impinges against the back of the buckets b b of the wheel, the latter, of course, fitting up cleanly to the under surface of the chute-box C, merely leaving enough space between them to allow of motion.

The buckets b b are placed in a corresponding circle to the chutes above them, but are more numerous, and are concave, or of such a form as will present a pocket to the impact of the water, yet not so much curved as to prevent the immediate discharge of water, so as to obviate the clogging of the wheel.

The wheel itself is fastened to the lower end of the vertical shaft f, which passes through it, and thence upward through the chute-box through an enclosing-tube, g, in the reservoir, out at the plate, where a pulley is attached to it for belt. Its upper bearing is a box, on the adjustable circle O, around the induction-pipe U. Their latter bearing is made movable, for the purpose of adjustment of the shaft, in case that the latter or the wheel may have shifted from a vertical or a horizontal position.

The lower end of the shaft is stepped on cross-arms connecting with the base of the machine, the supports of which I so arrange as to allow a space between them for the removal of the wheel D, for repairs, if necessary.

The base, as well as the flange n, is circular in the drawings, the former of lesser diameter than the latter, for the purpose of its insertion into the upper part of a chamber or draught-tube or duct of water, when the flange n would then rest on the rim of the tube or duct on which it was set, and could be made watertight, so as to secure a partial vacuum below the wheel, thus adding to the weight of the discharged water in its sucking action, so to speak, on the wheel and chutes.

The tube enclosing the shaft f is constructed so as to exclude all water from the shaft, by its close junction with the box below and the cover above, receiving as it does the nozzle of a short pipe above, around the opening in the plate or cover B, and a similar nozzle projecting from the chute-box below.

The gates a a have on their common uniting-ring, teeth engaging with the rack attached to a spindle, and worked by bevel-wheels and a hand-wheel at the top of the cylinder.

The operation of the machine is as follows:

The water being admitted through the nozzle U,

passes through the grating *h*, where such objects as would obstruct the chutes and wheel are kept back, and passing through the chute-box *C*, strikes the buckets of the water-wheel *D*, which being stationary on a shaft, *f*, which also carries a pulley on its upper end above the machine, affords the driving-power.

The speed is regulated by the gates *E*, managed by the rack.

Having thus fully described my invention,

What I claim therein as new, and desire to secure by Letters Patent, is—

The arrangement of the screen or grating *h*, sliding hatch *W*, adjustable circle *O*, with box embracing shaft *f*, induction-pipe *U*, and opening *V*, substantially in the manner and for the purposes as herein described.

JACOB HEPPERLY.
